Frederick W. Parker

UNITED STATES PATENT OFFICE

GEORGE P. HAYNES, OF BROOKLYN, NEW YORK, ASSIGNOR TO TODD DRY DOCK, ENGINEERING & REPAIR CORPORATION, OF NEW YORK, N. Y., A CORPORATION OF NEW YORK

PULVERIZED COAL BURNER

Application filed April 22, 1929. Serial No. 356,922.

This invention relates to methods of burning pulverized fuel in a furnace, and my improvements are directed to novel means, in conjunction with a furnace front, having a 5 burner projecting therethrough, wherein a pressure supply of air is communicated to said front for delivery to the burner in regulated quantities, whereby combustion of the fuel and propagation of the flame in the furnace are efficiently promoted.

Also my invention comprises the provision of an extended passage-way associated with the diaphragm which constitutes or forms part of the furnace front, for the passage of 15 air, for effecting heat exchange whereby the temperature of said diaphragm is prevented from becoming excessive, while the air heated in said extended passageway is available as a medium for drying the fuel and conveying 20 it to the burner.

Also my invention includes the provision of means, located in the fuel delivery passageway, for imparting a twist or spiral form to the column of fuel entering the burner, for 25 the purpose of enabling the combustion supporting air to mix more freely with the fuel in the burner.

Other features and advantages of my invention will hereinafter appear.

30 In the drawings:—

Figure 1 is a side sectional elevation of a furnace constructed in accordance with my invention and showing the fuel delivery and air supply means.

35 Fig. 2 is a front elevation of a two part structure provided with the extended air passageway for heat exchange.

Fig. 3 is a section on the line 3—3 of Fig. 2.

Fig. 4 is a horizontal section on the line 40 4—4 of Fig. 2.

Fig. 5 is a detail of the means for connecting the furnace front, diaphragm and burner flange.

In Figure 1 I have shown a portion of a 45 boiler 1 and a furnace composed of a corrugated shell 2, with fire brick lining 3 and an intermediate filling of refractory material 4 that extends out to a front plate or diaphragm 5, said diaphragm forming a boundary for 50 the mouth or entrance to the furnace. The

furnace in the example shown is provided with a hollow front that is composed of the forward plate 6 and annular wall 7 that connects with the shell 2.

The burner associated with the furnace, 55 indicated at 8, is of conoidal form, with its larger end opening into the furnace, a radial flange 9 at said larger end co-acting with the diaphragm 5 to close the furnace entrance exteriorly of the burner. 60

The burner has a forward cylindrical neck portion 10 that butts against the rearward end of a curved tubular section 11 which itself is a continuation of a curved fuel delivery tube 12, said tubular section 11 and 65 tube 12 having flanges 11a and 12a whereby they are secured together, as by bolts 11b.

Located in or adjacent to the boiler room is a blower 13, a pulverizer 14 adapted to supply pulverized coal to said blower, and a 70 hopper 15 to feed comminuted coal to said pulverizer, the hopper itself being replenished from a source of supply (not shown), as through an opening 16. As will be appreciated by those familiar with the art, pulverized coal is projected by the fan on the pulverizer through tube 12 for delivery to the 75 burner.

It is intended by me that heated air shall be supplied to the pulverizer as the vehicle 80 for conveying the pulverized coal from the fan of the pulverizer to the burner, for which purpose I have provided a pipe 17 that extends from the furnace front to said pulverizer. 85

As means for providing a source of adequately heated air to serve as the aforesaid vehicle there is shown within the hollow front a two part structure composed of the parts A—B, which together have approximately the shape of a horse-shoe, these parts A—B lying in front of the diaphragm 5 and having a rearwardly directed outside flange 18 that co-acts with said diaphragm to form an enclosed air space intermediate said two-part structure and diaphragm. Also said parts A—B are provided with an inner boundary flange 19 and with spaced webs 20, 21, which all co-act with the diaphragm to form therewith a return-bend or extended air 95 100

passage-way, whose course is indicated by the directional arrows in Fig. 2. Said extended passage-way is in communication with the interior of the hollow front by means of an ⁵ inlet port 22, it being understood that atmospheric air is supplied to said hollow front from the blower by means of a duct 23.

It is to be understood that the duct portion ¹⁰ 24, connecting duct 23 with the hollow furnace front herein illustrated, may also communicate air from the same blower to another furnace or to other furnaces (not shown) in association with the same boiler.

While the inlet port 22 is shown in communication with one end of the extended passage-way hereinbefore referred to, the pipe 17 is shown as connected with said extended passage-way at the other end thereof, so that a column of air traversing said ¹⁵ 20 passage-way, under pressure from said blower, will have its outlet through pipe 17, whence it will pass to the pulverizer for use, as before stated, in conveying pulverized coal to the burner.

²⁵ Since the two-part structure A—B is closely associated with diaphragm 5 it follows that air passing through the extended passage-way will serve the two-fold function of lowering the temperature of said diaphragm, thereby prolonging its life, while the temperature of the flowing stream of air is raised to a point at which it becomes more serviceable in promoting combustion of and drying the pulverized coal with which it is ³⁰ 35 laden when entering the burner.

The burner 8 is provided with an annularly disposed series of apertures 25, expanded from front to rear in the conoidal example of burner illustrated, for entry of ⁴⁰ the main supply of air from the hollow front to support combustion of the fuel and air mixture that enters the burner from tube 12 and tube section 11, vanes or deflectors 26 projecting inwardly respectively from edges ⁴⁵ of said apertures to give longitudinal direction to the streams of air entering the burner through said apertures, the spaces between the rearward edges 27 of the vanes and the rearward edges 28 of apertures 25 being ⁵⁰ 55 closed by members 29 to prevent the direct flow of air from apertures 25 into the furnace.

Supported axially within the rearward portion of tube section 11, just in advance of burner 8, is a deflector comprising radially ⁵⁵ disposed, inclined vanes 30, which have the effect of giving a whirling motion to the column of fuel and air entering the burner. Said column or mixture of fuel and air thus traversing the burner in whirling form receives the angular impingement thereon of supplies of air entering through apertures 25 and deflected by vanes 26, the thus directed streams of air having the effect of thoroughly carbureting the incoming air and resulting in ⁶⁰ 65 a highly combustible admixture of the main

supply of air with the fuel and air mixture.

It will be appreciated that the members or end closure means 29 check the direct forward flow of air that has entered the burner through apertures 25, and that in consequence the full volume of such air is caused by the vanes 26 to be impinged against and mingled with the stream of fuel and air mixture entering the burner, thereby achieving the described result. ⁷⁵

For the purpose of regulating the quantity of air supplied to the burner through apertures 25 I provide a register in the form of an annulus 31 about the burner, in revoluble relation therewith, said annulus having ports ⁸⁰ 32 to register with apertures 25, in full open position, and to vary the exposed areas of said apertures in other positions. The annulus 31, which is of conoidal contour to revolvably fit over the burner, has a cylindrical neck 33 ⁸⁵ that encircles the burner portion 10, and it abuts against a thrust bearing collar 34 that provides a joint between portion 10 and the rearward end of tube section 11.

As means for controlling the annulus ⁹⁰ 31 there is affixed thereto a gear segment 35, in mesh engagement with a pinion 36, carried by a shaft 37, that is journalled in a bearing 38 formed on the tube portion 11 and located within the hollow front. Said ⁹⁵ shaft 37 also penetrates a web 39 that extends from tube portion 11 outside the hollow front, and there engages an operating member for its rotation. Said operating member comprises a plate 40, having a handle 41 at one end and a pointer 42 at its other end, the pointer co-acting with a scale (not shown) on web 39 to indicate the adjusted position of the annulus. Also a set screw 43 is extended through plate 40, and adapted to ¹⁰⁰ 105 co-act with a plate 40' lying between web 39 and plate 6 of the hollow front, to secure the control means in an adjusted position of the annulus.

An oil burner is indicated at 44 as extended into the tube section 11, with its nozzle projected axially toward the burner, the purpose whereof is to supply oil for initially heating up the furnace, and also for operating the boiler at low pressure or otherwise. ¹¹⁰ 115

The oil burner is shown as supported by a formation 45 upon the tube section 11 and adjustably secured thereto by a set screw 46. The oil feed pipe is indicated at 47.

In the example indicated the outer tube of ¹²⁰ oil burner 44 is employed as the support for deflector 30.

At 48 there is indicated the usual furnace door.

Variations within the spirit and scope of ¹²⁵ my invention are equally comprehended by the foregoing disclosure:—

I claim:—

1. The combination with a furnace having a diaphragm forming the boundary for the ¹³⁰

entrance to the combustion chamber, and a pulverized fuel supply, of means providing an extended passage-way upon said diaphragm, means for introducing a stream of air into said passage-way, to effect exchange of heat with said diaphragm, and means for conducting the heated air from said passage-way to the fuel supply.

2. The combination with a furnace having a hollow front, and means for supplying air to the interior of said front, of a diaphragm forming the boundary for the entrance to the combustion chamber, having an extended passage-way formed thereon, coal pulverizing means, a burner projecting through said diaphragm, means of communication between said pulverizing means and said burner, means for introducing air from the interior of said hollow front into said passage-way, for heat exchange therewith, and means for conducting the heated air from said passage-way to the pulverizer, to serve as the vehicle for drying the pulverized coal and conveying it to the burner.

3. The combination with a furnace having a hollow front, a diaphragm forming the boundary for the entrance to the combustion chamber, and means for supplying air under pressure to the interior of said hollow front, of means providing an extended passage-way upon said diaphragm, means for introducing a current of air from the interior of said hollow front into said passage-way, to effect exchange of heat with said diaphragm, coal pulverizing means, a burner projecting through said diaphragm, means for conducting the heated air from said passage-way to said pulverizing means, and means of communication between said pulverizing means and said burner for the passage to the burner of the heated air laden with pulverized coal.

Executed this 18th day of April, 1929.
GEORGE P. HAYNES.
